UNITED STATES PATENT OFFICE.

SWAN J. LEVEEN, OF ROCK ISLAND, ILLINOIS, ASSIGNOR TO TRIO MANUFACTURING COMPANY, OF ROCK ISLAND, ILLINOIS, A CORPORATION OF ILLINOIS.

STARTING-SWITCH.

1,161,233.

Specification of Letters Patent.

Patented Nov. 23, 1915.

Application filed October 15, 1913. Serial No. 795,314.

To all whom it may concern:

Be it known that I, SWAN J. LEVEEN, a citizen of the United States, residing at Rock Island, in the county of Rock Island 5 and State of Illinois, have invented certain new and useful Improvements in Starting-Switches, of which the following is a specification.

The present invention relates to an improved construction of switch, and particularly to a switch adapted to service in connection with starting of smaller sizes of motor, as, for example, up to capacities of approximately five horse-power. However, 10 it will presently appear that the features of invention herein set forth and claimed are not restricted to switches intended for the foregoing sizes or capacities of motor, and, in fact, that said features may be used in 15 switches intended for other service than motor starting.

Under ordinary circumstances, the smaller sizes of motor may be started by connecting their terminals directly to the line or source 20 of electrical supply without the necessity of using a starting rheostat. In such cases, the starting current is generally considerably in excess of the running current. Even when a starting rheostat is used it frequently happens that the starting current is 25 of greater value or intensity than the normal running current. In either case, that current which is drawn during the starting operation is of abnormal value. By 30 reason of this fact, it frequently happens that the fuses, circuit breakers, or other protective devices, whose function is to protect the motor and line against overloads, are not set or adjusted to a high enough value 35 to properly carry the starting current. Consequently, these protective devices frequently operate to open the circuit during 40 the starting operation.

The switch of the present invention is so 45 designed and constructed that in the starting operation it may be first thrown to a position wherein the protective devices are bridged or cut out or shortcircuited during 50 the starting operation, but it is also so constructed that, after the motor or other device has come up to speed, or has attained 55 that condition in which it is drawing only a current of normal value, the protective devices may be thrown into service, so that thereafter the motor or other current con-

suming device and the line will be protected by the protective devices.

A further object of the invention is to so construct the switch and the operating mechanism whereby it is manipulated that 60 it is physically impossible to establish the connections in such manner as to include the protective devices in the first instance, thereby making it incumbent upon the operator to first throw the connections into that position wherein the protective devices are cut out. Thereafter, a further operation may be performed to cut the protecting devices back into service.

Another object of the invention is to so 70 construct the switch and its operating mechanisms that the various electrical contacts can be conveniently established and broken in an oil bath, thereby efficiently insulating these parts at all times, as well as 75 insuring an instantaneous extinguishing of the arc when the circuit is opened.

A still further object is to so construct the various contacts and operating mechanisms that the switch can be conveniently arranged with either one, two, three, or any desired number of poles, thereby adapting 80 the various features of the invention to use with single or polyphase currents, or with 85 direct current as desired.

A still further object of the invention is to so construct the various operating mechanisms that the contact carrying or circuit establishing devices will always be under a spring tension of such nature that, as soon 90 as the operating handle or other device is manipulated to a slight extent, the spring tension devices will operate to return the parts to their initial position. This will insure that, in the circuit opening process, the 95 contacts will not be re-established and maintained at the point where the protective devices are cut out, but will insure on the other hand that, once the opening movement commences, it will be carried through to 100 completion, thus completely opening the circuit and breaking the current.

Another object of the present invention is to so construct the containing or inclosing structure that the various electrical connections to the switch can be most conveniently made to the protective devices, such, for example, as the fuses. In this connection, the various circuits and contacts are so related 105 that when the switch stands in its initial or 110

open position the terminals of the protective devices will be dead, thus making it safe at such time to manipulate the protective device, for example, in replacing a fuse. 5 Nevertheless, the inclosing structure and other parts are so related that as long as the operating handle stands in the full on or running position the inclosing structure will be locked, thus making it impossible for the 10 operator to gain access to the protective devices, for any purpose whatsoever until the switch has been thrown to its off position.

Other objects and uses will appear from the various features of construction and 15 combinations of parts hereinafter described and claimed.

In the drawings: Figure 1 is a side view of the assembled switch structure, with the oil case in section to better show the mechanisms therein contained, the operating handle and contacts being shown in their initial or open position by full lines, and in the starting position by dotted lines; Fig. 2 is a view similar to that of Fig. 1, with the exception that the operating handle, contacts, etc., are shown in the starting position in full lines and in the running position in dotted lines; Fig. 3 is a section taken on the line 3—3 of Fig. 4, looking in the direction of the arrows; Fig. 4 is a front view of the assembled structure with the operating handle, contacts, etc., in running position, but with the lower portion of the switch structure and certain of the contacts 35 in section to better show the interior construction; and Fig. 5 is a plan view of the interior of the upper portion of the switch structure, showing particularly the arrangement of the terminal connections and protective devices. 40

Referring to the several figures, the switch structure in its entirety comprises two sections or compartments 6 and 7, best illustrated in Fig. 3. The upper compartment 45 6 serves to inclose the fuses or other protective devices, while the lower compartment 7 serves to inclose the contacts and operating mechanism, with the exception of the handle and starting lock. Between these two compartments there is a partition 8 of 50 insulating material, such as slate or the like, said partition preferably being carried by or mounted in the lower portion of the upper compartment. This insulating partition 55 supports all of the stationary contacts or supporting devices, as well as serving to divide the two compartments from each other.

The upper compartment is preferably 60 made from a U-shaped sheet metal inclosure 9, which serves to provide the side walls and back of the upper compartment. Another section of sheet metal 10 extends across the front ends of the U-shaped section, and is 65 secured thereto in any suitable manner, as

by means of spot welds or the like. As shown particularly in Figs. 1, 2, and 3, the side walls of the upper compartment are preferably higher in their rear portions than in their front portions, and their upper 70 edges slant downwardly toward the front. Across the rear portions of the side walls there is mounted a cover 11, which preferably has its rear and side portions bent downwardly to provide the inclosing 75 flanges 12. These in turn may be conveniently attached to the U-shaped member as by means of the screws 13. A door 14 is hinged to the cover 11 by the hinges 15, said door having the downwardly depending side 80 flanges 16 which embrace the side walls of the U-shaped member between them, as best shown in Fig. 4. The upper edge of the front 10 is preferably flanged rearwardly to provide the lip 17 against which the front 85 edge of the door rests, and a lock 18, carried by the door, is adapted to engage the under face of this lip for normally locking the door closed. This lock 18 is conveniently attached to the lower end of an eye 19. For this purpose, the stem of this eye extends through the door, or through a bushing 20 carried thereby, and has its lower end split to provide a pair of fingers 21 which engage a somewhat elongated hole in the lock 18, as 90 best shown in Fig. 3. The entire switch structure may be conveniently supported on a wall or post by means of a pair of cross-wise extending bars or plates 22 secured to the back of the U-shaped member. 95

In the particular arrangement illustrated, the insulating partition is supported on flanges 23 which are in turn supported by or inturned from the side walls of the U-shaped structure, as best shown in Figs. 3, 4, and 5, 100 screws or the like 24 holding the partition rigidly in position. A pair of angles or the like 25 depend from the flanges 23 and serve to support a box-like structure 26 which incloses the lower or contact compartment 105 of the switch. Screws or the like 27 serve as a ready means for attaching this box-like structure to the flanges 25, so that the box-like structure can be readily removed for 110 purposes of examining or adjusting the contacts, or for the purpose of renewing or replenishing the oil. This box-like structure serves as the pan or container for the oil which protects the contacts and serves to establish the oil breaks, and it will presently 115 appear that all of the contacts are sufficiently low down to be thoroughly covered over by the oil.

It is preferred that the front plate 10 and the rear side of the U-shaped member should 120 extend down somewhat below the partition 8, as best shown in Figs. 1, 2, and 3, so that they serve to provide the flanges or sills 28 and 29 for quickly centering the box-like structure and for covering over the upper 125

edges of its front and rear sides. On the other hand, as shown in Fig. 4, the angles 25 are set in a slight distance from the side faces of the U-shaped member, so that when the box-like structure is set in position its upper edges 30 and 31 will lie flush with the outer faces of the U-shaped member.

In the particular construction illustrated, I have provided three sets of contacts, and correspondingly three fuses or other protective devices. This arrangement is well adapted to use in connection with three phase current, but, as previously stated, the invention is in nowise limited to this number of sets of contacts.

Corresponding to each set of contacts there is a pair of bushings or the like 32 and 33 in the cover 11. The bushings 32 are for the incoming or line wires, while the bushings 33 are for the outgoing wires which lead to the motor or other device to which the current is supplied. In the lower rear portion of the upper compartment, there is mounted an upstanding connector 34 corresponding to each of the bushings 32, and in the particular arrangement illustrated, each of these connectors is carried by an L-shaped bar 35 which is secured to a crosswise extending insulating bar or rod 36 which, in turn, is mounted on the rear portion of the insulating partition 8. This arrangement is best illustrated in Figs. 3 and 5. Corresponding to each of the outgoing bushings 33 there is a connector 37, and these connectors in turn are carried by the L-shaped bars 38 which run down into and are secured to the terminal blocks 39. These terminal blocks are made of insulating material, such as porcelain or the like, being open only on their front and top sides, and being mounted in turn on the insulating partition 8. Corresponding to each of the terminal blocks 39 is another terminal block 40 set over near the front edge of the insulating partition 8, and likewise having its rear and top sides open. These terminal blocks serve as mountings for the clips 41 into which fuses or other protective devices 42 may be inserted in the customary manner. The terminal blocks 39 and 40 serve as an efficient means for thoroughly insulating from each other the exposed clips and conducting portions into which the fuses are inserted, so that there is no danger of arcing over from one conductor to another. Furthermore by setting the terminal blocks 39 and 40 in the forward portion of the upper compartment 6, they are easily accessible through the door 14, and it is not necessary for the operator to reach back far enough to touch any of the live contacts 34 in manipulating either the contacts 37 or the fuses.

In the lower compartment 7, there is mounted or supported a contact 43 corresponding to each of the incoming line wires.

These contacts are preferably mounted in an upstanding position, such as best illustrated in Figs. 2 and 3, and for this purpose each is conveniently carried on the forward end of a rod or bar 44 of conducting material. All of the rods or bars 44 are carried by an insulating block 45 which extends across the rear portion of the compartment 7, and is conveniently secured to the rear portion of the insulating partition 8. As a convenient means of securing each bar 44 in place, and for securing the corresponding bar 35 in place, and for joining both of these bars together, a bolt or the like 46 may be extended up and down through the insulating blocks 36 and 45 and through the insulating partition, as best shown in Fig. 3. This bolt, therefore, serves to deliver the current to the bar 44. It will thus be noted that the contacts 43 are alive as long as the contacts 34 are connected to the source of electrical supply.

Corresponding to each of the contacts 43 is another downwardly extending contact 47 which in turn is carried by a rod or bar 48 of conducting material. All of the rods or bars 48 are supported by a crosswise extending bar of insulating material 49 which is supported on the insulating partition, and a bolt or the like 50, extends through each rod or bar 48, and the corresponding bar 38, and serves to hold the bars 48 and 38 in position and to establish electrical connection between them. It will be noted that when an electrical connection is established between each of the contacts 47 and the corresponding contact 43, the wire connected to the corresponding connector 37 is electrified without the necessity of the current passing through the fuse.

Corresponding to each of the contacts 43 is a downwardly extending contact 51, preferably in the form of an L-shaped bar of conducting material. The contacts 51 in turn are carried by a bar or block of insulating material 52 which is supported by the forward portion of the insulating partition, a bolt or the like 53 serving to secure each contact 51 and the corresponding fuse clips in place, and serving also to establish electrical connection between them. It will be noted that whenever electrical connection is established between a contact 43 and the corresponding contact 51, but not with the contact 47, the corresponding connector 37 will be electrified through the fuse, or other protective device.

I have provided means for establishing electrical connection from each of the contacts 43 either to the corresponding contact 47 or to the corresponding contact 51. When the first form of connection is established, which I shall designate a starting connection, the fuses or other protective devices are cut out or bridged so that the starting

current does not need to pass through them. On the other hand when the connection is established by way of a contact 51, the fuses or other protective devices are cut into service, and thence forth will serve to protect the circuits of which they constitute a part. As a convenient means of establishing these various connections, I provide a vertically movable bar of insulating material 54 which carries a U-shaped contact member 55 corresponding to each of the contacts 43. Each U-shaped member has the upstanding contact arms 56 and 57, the former of which may engage either the contact 47 or the contact 43, or both of said contacts simultaneously. The upstanding contact arm 57 on the other hand always rides against the downwardly depending contact 51. The normal or open circuit position of the bar 54 is the up position, as shown in Fig. 1. When in this position, no connection is established to the contacts 43, and, therefore, current is not supplied to the motor or other consuming device. The starting position of the bar 54 is that illustrated in full lines in Fig. 2, wherein it will be noted that, although the contact 51 is electrified, still a connection is established directly from each of the contacts 43 to the corresponding contact 47, thus supplying the current directly to the motor without having to pass through the fuses. In this way, the fuses are bridged or shunted during the starting operation. The running position is that shown in dotted lines in Fig. 2, or in full lines in Fig. 3, in which it will be seen that the connection to the contacts 47 has been broken, so that the current must pass to the motor by way of the fuses or other protective devices.

It will be noted that when the circuit breaks on the opening operation the break is always between the U-shaped member 55 and the corresponding contact 43. This break takes place comparatively low down in the compartment 7, and therefore well under the surface of the oil therein contained. For this reason, the break is accomplished in the most efficient and satisfactory manner, and with the least possible amount of burning. However, in case it should be desired to renew any of the contacts 43, such renewal can be easily effected when the switch stands in its idle position, because at such time said contacts are not obstructed or interfered with by any of the other contacts. This fact is well illustrated in Fig. 1.

It is desired to permit the maximum range of adjustability or adaptability in the movements of the bar 54, so as to insure that the contacts will always be established in the most natural and effective manner. For this purpose, this bar is so supported that it can have a certain amount of rotary adjustment

should that be necessary or desirable. Adjacent each end of the bar 54 there is mounted a swinging arm 58 pivoted to the insulating block 45. As a convenient means of effecting this pivotal connection, I extend a rod 59 the entire length of the block 45 and behind the same, and the arms 58 are pivoted on said rod, being held in place by cotter pins or the like 60, shown in Figs. 1 and 2. A pair of hooks or the like 61 extend through the block 45, and serve to secure the rod to it.

The forward ends of the bars 58 are slotted as at 62 in Figs. 1 and 2, to accommodate the pins 63 secured to the ends of the bar 54. By reason of this slotted connection the bar 54 is permitted to have a straight up and down or rectilinear motion regardless of the angularity due to the swing of the arms 58. Owing to the pin and slot connection thus established, the bar 54 is free to turn whatever amount may be necessary in order to secure the aforementioned effective contact.

Extended across the upper portion of the compartment 7 and journaled in the angles 25 is an operating rock shaft 64, one end of which projects outside of the casing and carries the operating handle 65. This handle may be provided with a button 66 of customary form. Above the upper ends of the bar 54 the operating rock shaft carries a pair of crank arms or the like 67. These crank arms are extended through holes in the operating rock shaft and have their outer ends 68 bent at an angle to serve as journals for connecting links 69 which establish connection from the crank arms to the pins 63 which are carried by the ends of the bar 54. It will thus be seen that as the operating rock shaft is rotated the bar 54 will be raised or lowered, as desired. Corresponding to each of the crank arms 67 is a triangular-shaped plate 70 which is loosely mounted on the operating rock shaft, and one arm extending down slightly beyond the bent portion 68 of the corresponding crank. This portion 68 extends through the plate 70, a cotter pin or the like 71 serving to hold the link and plate in position on the end of the crank. The other arm 72 of the triangular-shaped plate is adapted to strike or engage a stationary abutment, as, for example, the corresponding angle 25, and thus serve to limit the rotating movement of the operating rock shaft and crank. A washer or the like 73, best shown in Fig. 4, is mounted between each of the plates 70 and the corresponding angle, and serves to hold said plate up against the crank arm. The arrangement just described is such that the crank 67 and the triangular plate 70 do not have to be tightly fitted to the shaft in order to cause them to properly perform their

functions. The chief function of the cranks is to force the bar 54 downwardly through the medium of the links 69, and the chief function of the triangular-shaped plates is to prevent the cranks from slipping up and down in the holes of the operating rock shaft, and to serve as stops to limit the forward movement of the rock shaft. By using this construction, it will be seen that 10 both of the holes which accommodate the cranks can be accurately drilled parallel to each other, and then the cranks can be inserted with definite assurance that they will operate in unison for the control of the 15 movement of the bar 54.

A pair of springs 74 tend to raise the arms 58 for the purpose of restoring the bar 54 to its initial position. The parts are so proportioned that by the time the triangular-shaped plates perform their function of limiting rotation of the operating rock shaft a toggle effect is produced, as best shown in Fig. 3, so that the springs will hold the contacts locked in the position illustrated in 25 said figure. However, as soon as the operating rock shaft has been forced back through a small angle, the tendency of said springs will be reversed, and the bar 54 will be thrown up quickly and positively to open 30 the circuit and restore the parts to their initial or open circuit position.

It is desired to provide means for temporarily but positively arresting the movement of the bar 54 during a starting operation when said bar reaches the position shown in Fig. 2, which is the starting position. In the present arrangement I have illustrated such means as in the form of a mechanism or device which operates in connection with the operating handle 65, but manifestly any other suitable arrangement can be used. In the arrangement illustrated the handle is provided with a lug or catch portion 75. On the side of the inclosing 45 structure, there is pivoted a triangular-shaped plate 76, the pivotal point being at 77, and said plate is provided with an outstanding abutment or barrier 78 which at times interferes with the movement of the 50 handle by reason of the engagement of the lug 75 therewith. Pins or the like 79 and 80 serve to limit the swinging movement of the triangular-shaped plate in both directions, although the pin 80 may be dispensed with 55 if desired.

The plate 76 is of such shape and is pivoted at such a point that when it stands in its normal position, as shown in Fig. 1, the lug 75 will strike against the barrier 78 when 60 the handle has been moved up to the starting position, and by reason of the presence of the pin 79 the swinging movement of the plate will be arrested at such time so that it will be impossible to throw the starting han-

dle farther forward in order to establish the 65 running connection. In Fig. 2, I have shown by the dotted lines 81 the position of the plate 76 corresponding to that shown in Fig. 1—that is, the normal position. If, after the handle has been thrown into the 70 position shown in Fig. 2, and the motor or other device has been allowed to come up to speed, so that the normal operating current is reached, the handle be suddenly forced back a slight distance, the plate 76 75 will swing or oscillate over into the position shown by the dotted lines 82 of Fig. 2, in which position the barrier 78 will not interfere with the movement of the lug 75. Thereupon the handle may be thrown clear 80 over to running position. It will be seen that in order to reach or attain the running position, it was necessary to bring the handle into the position shown in Fig. 2, and to arrest it in such position, thus preventing 85 the operator from throwing it clear over to the running position which would subject the fuses or other protective devices at once to the starting current.

In order to lock the door against opening 90 when the handle stands in running position, I have provided a lip or lug 83 on said door, which lip or lug is adapted to be engaged by the lug 75 of the operating handle when the latter is thrown into running position. The 95 engagement of the lug 75 with the lug 83 will not be broken until the toggle connection has passed its center, so that assurance is had that the switch will travel clear over to the open position when it is desired to 100 open the door in order to reach the fuses.

In order to prevent endwise movement of the bar 54, and in order to better guide the same in its vertical movements, I have provided the slots or grooves 84, best shown in 105 Fig. 4, in which ride the contacts 51 and 43.

It will be noted that in the process of changing over from the starting to the running connections the circuits to the motor or other current consuming device are not 110 opened, but that on the other hand these circuits remain unbroken, so that the current supply also remains unbroken. This is a very desirable feature in a starting switch for any purpose, but particularly in a starting switch which is used in connection with a motor. Frequently the motors are started up under load, so that even a momentary pause in the supply of current will allow the motor to drop back in speed a considerable 120 amount, and therefore cause the current demand to be abnormally large when the switch is thrown to the running position. This disadvantage is, of course, overcome in switches embodying features of my invention 125 wherein the current supply is unbroken. Or, for example, it is extremely desirable to maintain the current supply to a synchro-

nous motor during the operation of changing the starting switch over from the starting to the running position, inasmuch as a break in the current supply at such time might 5 allow the motor to fall out of step. It will also be observed that the foregoing advantage of changing over from one set of connections to the other without opening the circuit is obtained with a sliding contact, 10 and also within the oil bath, so that sparking, etc. is reduced to a minimum.

It will be understood that I do not in any wise limit myself to the features of construction illustrated and described herein, except 15 as may be called for in the claims, but I include within the scope of my invention any equivalent constructions operating in an equivalent manner to produce equivalent results.

20 I claim:

1. In a starting switch, the combination of an incoming line terminal, an outgoing delivery terminal, a protective device, an enclosure within which said protective device 25 is mounted, a door for giving access to the protective device within the interior of said closure, said protective device being normally electrically disconnected from the incoming line terminal, means for electrically 30 connecting said protective device to the incoming line terminal, a spring tending to restore said connecting means to initial or unconnected position, means for retaining said connecting device in operated or running position, 35 and means for locking said door against opening while said connecting device remains in operated or running position.

2. In a starting switch, the combination of an incoming line terminal, an outgoing delivery terminal, fuse clips adapted to the reception of an electric fuse, an enclosure within which said clips and fuse are mounted, a door in said enclosure for giving access to said clips and fuse, said clips being normally 45 electrically disconnected from the incoming line terminal, means for establishing an electric circuit, including the incoming line terminal, fuse clips and fuse, and means for locking said door against opening while said 50 circuit is established.

3. In a starting switch, the combination of an incoming line terminal, an outgoing delivery terminal, a protective device, an enclosure within which said protective device 55 is mounted, a door for giving access to the interior of said enclosure for the purpose of reaching the protective device, said protective device being normally electrically disconnected from the incoming line terminal, 60 a toggle actuated switch mechanism for establishing an electrical circuit, including the incoming line terminal and the protective device, a spring for returning said toggle switch to initial or open circuit position

wherein the protective device is electrically 65 disconnected from the incoming line terminal, and means for locking said door in closed position when the toggle mechanism stands in closed circuit position.

4. In a starting switch, the combination of 70 an incoming line terminal, an outgoing delivery terminal, a protective device, an enclosure within which said protective device is mounted, a door within said enclosure for giving access to the protective device, said 75 protective device being normally electrically disconnected from the incoming line terminal, means for establishing an electric circuit, including the incoming line terminal and said protective device, and means for 80 locking said door while said circuit is established.

5. In a starting switch, the combination of 85 an incoming line contact, a starting contact, and a running contact, a movable contacting member adapted to establish electrical connection from the incoming line contact either to the starting contact or to the running contact alone, a spring normally holding the contacting member in initial or open 90 circuit position, an operative rock shaft, a toggle connection from the operative shaft to the contacting member, a handle for rotating the operative rock shaft, a door for giving access to the interior of the structure, and a portion on the handle adapted to 95 engage a portion on the door for locking the door against opening before the toggle action is reversed.

6. In a starting switch, the combination of 100 an incoming line contact, a starting contact, and a running contact, a contacting member adapted to place the incoming line contact in electrical connection either with the starting contact or with the running contact 105 alone, a spring normally holding said contacting member in initial or open circuit position, an operative rock shaft, a toggle connection from the operative rock shaft to the contacting member, means for limiting the 110 rotary movement of the operative rock shaft when the toggle action has reversed, a door for giving access to the interior of the structure, and means for locking said door against opening while the toggle action is reversed. 115

7. In a starting switch, the combination of 120 an incoming line contact, a starting contact, and a running contact opposite to both of said contacts, an insulating block adapted to travel between the running contact and the starting and incoming line contacts, a contact carried by said block, a spring normally holding the insulating block in initial or open circuit position, an operative rock 125 shaft, a toggle action from said operative rock shaft to the insulating block, means for limiting the rotary movement of the oper-

ative rock shaft when the toggle operation has reversed, and a handle for operating the rock shaft.

8. In a starting switch, the combination of 5 an incoming line contact, a starting contact, and a running contact, an insulating block adapted to travel between the running contact and the starting contact or the incoming line contact, a contact carried by said block, 10 a spring normally holding the insulating block in initial or open circuit position, an operative rock shaft, a toggle action from the operative rock shaft to the insulating block, and means for limiting the rotary 15 movement of the rock shaft when the toggle operation has reversed.

9. In a starting switch, the combination of 20 an incoming line contact, a starting contact parallel thereto, and a running contact opposite to both of said contacts, an insulating block adapted to travel between the running contact and the starting contact and incoming line contact, a contacting member carried by said insulating block, a spring normally 25 holding the insulating block in initial or open circuit position, an operative rock shaft, a crank carried thereby, a link from said crank to the insulating block, and means for limiting the rotary movement of the rock shaft when the crank and link have passed 30 dead center.

10. In a starting switch, the combination of 35 an incoming line contact having a contact face, a starting contact having a contacting face in alignment with the contacting face of the incoming line contact, a running contact having a contacting face opposite to the contacting face of the incoming line contact, an insulating block adapted to travel between 40 the incoming line contact and the running contact and in the direction of their contacting faces, a contacting member carried by said insulating block and adapted to establish electrical connection either between the 45 incoming line contact, the running contact and the starting contact, or between the incoming line contact and the running contact alone, a spring for normally holding the insulating block at the initial or open circuit 50 position, an operative rock shaft, a crank carried thereby, and a link connection from the crank to the insulating block.

11. In a starting switch, the combination of 55 an incoming line contact having a contacting face, a starting contact having a contacting face in alignment with the contacting face of the incoming line contact, a running contact having a contacting face opposite to the contacting face of the incoming line contact, an insulating block adapted to travel between the incoming line contact and the running contact and in the direction of their contacting faces, a contacting member carried by said insulating block, a spring

normally holding the insulating block in 65 initial or open circuit position, and a toggle action to said insulating block for forcing the same against the tension of the spring to a position where electrical connection is established between the incoming line contact and the running contact where the toggle action reverses, whereby the spring tends to hold the insulating block in such position.

12. In a starting switch, the combination 75 of an incoming line contact having a contacting face, a starting contact having a contacting face in line with the contacting face of the incoming line contact, a running contact opposite the incoming line contact, an 80 insulating block adapted to travel in the direction of the said contacting faces and between the incoming line contact and the running contact, a contact carried by said block and adapted to establish electrical connection 85 between the incoming line contact and the starting contact, or only between the incoming line contact and the running contact, a spring normally holding the insulating block in initial or open circuit position, 90 means for forcing the insulating block against the tension of the spring to carry the contacting member into position to establish electrical connection between the incoming line and the starting contact, or between 95 the incoming line contact and the running contact, and means for positively arresting the movement of the insulating block in its forward direction when it reaches a position to establish connection from the 100 incoming line contact to the starting contact.

13. In a starting switch, the combination of an incoming line contact having a contact face, a starting contact having a contacting face in line with the contacting face 105 of the incoming line contact, a running contact having a contacting face opposite to the contacting face of the incoming line contact, an insulating block adapted to travel between the incoming line contact and the 110 running contact and in the direction of their contacting faces, a contacting member carried by said insulating block and adapted to at times establish electrical connection between the incoming line contact the running 115 contact and the starting contact, or between the incoming line contact and the running contact alone, a spring normally retaining said insulating block in position where the contacting member is out of engagement 120 from the incoming line contact, and means for forcing said insulating block against the tension of said spring to carry the contacting member into engagement with the incoming line contact.

14. In a starting switch, the combination of a plurality of electrical contacts having parallel contacting faces, an insulating block

- adapted to travel between said contacts in the direction of their contacting faces, a U-shaped contact carried by said insulating block and having its arms in engagement with parallel contacting faces, and a pivotal mounting for said insulating block to permit the same to travel with a firm and even contact of the U-shaped contactor against the parallel contacting faces.
- 10 15. In a starting switch, the combination of an incoming line terminal, an outgoing delivery terminal, a protective device, an incoming line contact electrically connected to the incoming line terminal and having a vertical contacting face, a starting contact electrically connected to the outgoing delivery terminal and having a vertical contacting face in alinement with the contacting face of the incoming line contact, a running contact electrically connected to one side of the protective device and having a vertical contacting face opposite to the contacting face of the incoming line contact, a vertically movable insulating block adapted to travel between the incoming line contact and the running contact, a U-shaped contact carried by said block and adapted to simultaneously engage the incoming line contact and the running contact when the insulating block is in running position, and adapted to simultaneously engage the incoming line contact, the starting contact, and the running contact when the insulating block is in starting position, and a pivotal mounting for said insulating block to permit the U-shaped contact carried thereby to accommodate itself to a firm engagement with both the incoming line contact and the running contact.
- 20 25 30 35 40 45 50 55 60 65 70 75 80 85 90 95 100 105 110 115 120 125
16. In a starting switch, the combination of an incoming line terminal, an outgoing delivery terminal, a protective device, an incoming line contact having a vertical contacting face and in electrical connection with the incoming line terminal, a starting contact electrically connected to the outgoing line terminal and having a vertical contacting face in alinement with the contacting face of the incoming line contact, a running contact having a vertical contacting face opposite to the contacting face of the incoming line contact, an electrical connection from the running contact to one side of the protective device, an electrical connection from the other side of the protective device to the outgoing line terminal, and a vertically movable contact block adapted to travel between the contacting faces of the incoming line contact and of the running contact.
17. In a starting switch, the combination of an incoming line terminal, an outgoing delivery terminal, a protective device, an incoming line contact electrically connected to the incoming line terminal, a starting contact mounted at a higher elevation than the incoming line contact and electrically connected to the outgoing delivery terminal, a running contact electrically connected to one side of the protective device, an electrical connection from the other side of the protective device to the outgoing delivery terminal, and a vertically movable contact adapted to establish electrical connection from the incoming line contact either to the starting contact or to the running contact, whereby said movable contact stands at a higher elevation than the incoming line contact when in idle position to facilitate access to the incoming line contact when in such position.
18. In a starting switch, the combination of an incoming line terminal, an outgoing delivery terminal, a protective device, an upwardly extending line contact electrically connected to the incoming line terminal, a starting contact mounted above the incoming line contact, and electrically connected to the outgoing line terminal, a running contact electrically connected to one side of the protective device, an electrical connection from the other side of the protective device to the outgoing line terminal, a movable contact adapted to establish electrical connection from the incoming line contact either to the starting contact and the running contact or to the running contact alone, and an oil bath immersing all of said contacts.
19. In a starting switch, the combination of an incoming line terminal, an outgoing delivery terminal, a protective device, an upwardly extending line contact electrically connected to the incoming line terminal, a downwardly depending starting contact mounted above the line contact, and electrically connected to the outgoing delivery terminal, a downwardly depending running contact electrically connected to one side of the protective device, an electrical connection from the other side of the protective device to the outgoing delivery terminal, and a movable contact adapted to place the incoming line contact in electrical connection with the outgoing delivery terminal either direct by way of the outgoing line contact, or only by way of the contact connected to the protective device.
20. In a device of the class described, the combination of an incoming line terminal, an outgoing delivery terminal, and a protective device, of a traveling contact adapted to first establish connection from the incoming line terminal direct to the outgoing delivery terminal, and afterward from the incoming line terminal to the outgoing delivery terminal only through the protective device when said movable contact is moved in a given direction, the last mentioned connection being

established prior to the breaking of the first mentioned connection.

21. In a device of the class described, the combination with an incoming line terminal, 5 an outgoing delivery terminal, and a protective device, of a traveling contact adapted to first establish connection from the incoming line terminal direct to the outgoing delivery terminal, and also to the outgoing delivery 10 terminal by way of the protective device, and afterward to establish connection from the incoming line terminal to the outgoing delivery terminal only by way of the protective device when moved in a given direction, and means for positively arresting the traveling contact after the first mentioned connection has been established and before the last mentioned connection is established. 15
